Eig - 1

Fig. 3

Fig. 2

FIG. 4

FIG. 1 is a perspective view of a vacuum coaxial relay, showing my new design.

FIG. 2 is a side elevational view taken from the left side of FIG. 1.

FIG. 3 is a side elevational view taken from the right side of FIG. 1.

FIG. 4 is an elevation of the vacuum coaxial relay as viewed from the rear of FIG. 1.

FIG. 5 is a top plan view as seen from above in FIG. 1.

FIG. 6 is a bottom plan view as seen from below FIG. 1.

I claim:

The ornamental design for a vacuum coaxial relay, as shown.
